UNITED STATES PATENT OFFICE

114,450

DESIGN FOR A FINGER RING

Julius Lannes, Chicago, Ill.

Application November 5, 1938, Serial No. 80,896

Term of patent 3½ years

To all whom it may concern:

Be it known that I, Julius Lannes, a citizen of the United States of America, residing at Chicago, in the county of Cook and State of Illinois, have invented a new, original, and ornamental Design for Finger Rings, of which the following is a specification, reference being had to the accompanying drawing, forming a part thereof.

Fig. 1 is a side elevational view of a finger ring showing my new design.

Fig. 2 is a fragmentary view of one facet of the ring, the view being taken on line 2—2 of Fig. 1, there being four identical facets, and

Fig. 3 is a fragmentary view of one facet of the ring, the view being taken on line 3—3 of Fig. 1, there being four identical facets.

I claim:

The ornamental design for a finger ring, as shown and described.

JULIUS LANNES.
